DESIGN FOR A COUNTER

Clifford Brooks Stevens, Milwaukee, Wis., assignor
to Durant Manufacturing Company, Milwaukee,
Wis., a corporation of Wisconsin

Application December 8, 1938, Serial No. 81,636

Term of patent 7 years

To all whom it may concern:

Be it known that I, Clifford Brooks Stevens, a citizen of the United States, residing at Milwaukee, in the county of Milwaukee and State of Wisconsin, have invented a new, original, and ornamental Design for a Counter, of which the following is a specification, reference being had to the accompanying drawing, forming part thereof.

In the drawing:

Fig. 1 is a perspective view of a counter embodying my new design;

Fig. 2 is a top view of the counter; and

Fig. 3 is an end view of the counter.

The dominant or characteristic features of my design are shown in solid lines.

I claim:

The ornamental design for a counter, substantially as shown and described.

CLIFFORD BROOKS STEVENS.
